ABSTRACT: A ring counter having a one count delay during each cycle is used to clock a Johnson counter during the one count delay. A number of individually identifiable clock pulses are then available for clocking and sequential control functions by ANDing any one of the outputs of the ring counter with any one of the outputs of the Johnson counter, the total number being equal to the product of the number of ring counter outputs and the number of Johnson counter outputs.

CLOCKING SYSTEM

BACKGROUND OF THE INVENTION

This invention relates generally to digital systems, and more particularly relates to a system for producing a number of individually identifiable clock pulses which occur in a predetermined sequence.

In digital logic systems such as, for example, computers, data processors and automated control systems, it is often necessary to utilize a sequence control having a number of individually identifiable pulses which occur in a predetermined sequence. Perhaps the most apparent solution to this problem is to provide a ring counter having the desired number of outputs, although a binary counter with a suitable binary-to-numerical decoder might also be used. However, these approaches require a relatively large number of circuit components and are not wholly satisfactory.

SUMMARY OF INVENTION CLAIMED

A first counter having a plurality of outputs for sequentially producing a pulse on each output, then after a delay period, repeating the sequence, and a second counter having a plurality of outputs for sequentially producing a pulse on each output and then repeating the sequence, the second counter being clocked by the first counter during the delay period. More specifically, the first counter is preferably a ring counter including a delay stage, and the second counter is a Johnson counter which is clocked through a delay circuit by the last output from the ring counter preceding the delay period.

BRIEF DESCRIPTION OF THE DRAWINGS

FIG. 1 is a schematic logic diagram of a clocking system in accordance with the present invention;

FIG. 2 is a logic diagram illustrating the operation of the ring counter of the clocking system of FIG. 1;

FIG. 3 is a logic table illustrating the operation of the Johnson counter of the clocking system of FIG. 1;

FIG. 4 is a timing diagram illustrating the state of the outputs T_1-T_8 of the Johnson counter during each cycle; and

FIG. 5 is a timing diagram illustrating the operation of the clocking system of FIG. 1.

DESCRIPTION OF A PREFERRED EMBODIMENT

Referring now to the drawings, a clocking system in accordance with the present invention is indicated generally by the reference numeral 10 in FIG. 1. The clocking system 10 is comprised of a ring counter indicated generally by the reference numeral 12 having four binary stages RC_1 , RC_2 , RC_3 and RC_4 . Each of the binary stages may comprise a conventional J-K flip-flop having J and K inputs and true and complement outputs T and C, respectively, as indicated. The J-K flip-flops assume a state after each clock pulse from an oscillator 14 that is dependent upon the state of the inputs prior to the clock pulse. If a logic 1 is applied to the J input and a logic 0 to the K input, the flip-flop will assume a logic 1 state with the true output T at a logic 1 level. If the J input is a logic 0 and the K input a logic 1, the flip-flop will assume a logic 0 state after the clock pulse with the true output a logic 0 level. The conditions when both J and K inputs are a logic 1 and when both J and K inputs are a logic 0 are not used.

The binary stages RC_1 – RC_4 are connected with the true output T of stage RC_1 connected to the J input of stage RC_2 , the true output T of stage RC_2 connected to the J input of stage RC_3 , and the true output T of stage RC_3 connected to the J input of stage RC_4 . The true output T of each of the stages RC_1 – RC_4 is also connected back to the K input of the stage so that the stage will automatically be set back to the logic 0 state on the first clock pulse after going to a logic 1 state. The complement outputs C of all four stages RC_1 – RC_4 are connected back to the inputs of an AND gate 16, and the output of AND gate 16 is connected to the J input of stage RC_1 . The true output T of stages RC_1 – RC_4 are connected to the outputs P_1 – P_4 , respectively, of the ring counter 12.

The true output T of stage RC_4 is connected through an inverting amplifier 18 to the clock inputs of each of the four stages JC_1 , JC_2 , JC_3 and JC_4 of a Johnson counter indicated generally by the reference numeral 19. Johnson counters of the type disclosed herein are described in U.S. Patent No. 2,853,238 issued to R. R. Johnson on Sept. 23, 1958. Each of the stages JC_1 – JC_4 may also comprise a conventional J-K flip-flop. The true and complement outputs of stage JC_1 are connected to the J and K inputs, respectively, of stage JC_2 ; the true and complement outputs of stage JC_2 are connected to the J and K inputs, respectively, of stage JC_3 ; and the true and complement outputs of stage JC_3 are connected to the J and K inputs, respectively, of stage JC_4 . However, the true and complement outputs of stage JC_4 are connected to the K and J inputs, respectively, of stage JC_1 . In addition, the complement outputs of stages JC_1 and JC_4 are connected to the inputs of a NAND gate 20 the output of which is connected through an inverting amplifier 22 to the reset inputs of stages JC_2 and JC_3 . This is to prevent the counter from operating in the illegal mode.

The true and complement outputs of stages JC_1 – JC_4 are connected to the inputs of a bank of NAND gates G_1 – G_8 . The output of each of the NAND gates is connected to inverting amplifiers D_0 – D_7 having outputs T_1 – T_8 , respectively. The inputs to gate G_1 are taken from the complement outputs of stages JC_1 and JC_4 . The inputs of gate G_2 are taken from the true output of stage JC_1 and the complement output of stage JC_2 . The inputs of gate G_3 are taken from the true output of stage JC_2 and the complement output of stage JC_3 . The inputs of gate G_4 are taken from the true output of stage JC_3 and the complement output of stage JC_4 , the inputs of gate G_5 are taken from the true output of stage JC_1 and the true output of stage JC_4 , the inputs of gate G_6 are taken from the complement output of stage JC_1 and the true output of stage JC_2 , the inputs to gate G_7 are taken from the complement output of stage JC_2 and the true output of stage JC_3 , and the inputs of gate G_8 are taken from the complement output of stage JC_3 and the true output of stage JC_4 .

OPERATION

The operation of the ring counter 12 may best be understood by referring to FIG. 2. Assume that after a clock pulse t_0 from the oscillator 14, all of the stages RC_1 – RC_4 are at a logic 0 state. The logic 1 levels of the complement outputs will then satisfy the inputs of the gate 16 so that a logic 1 level will be applied to the J input of stage RC_1 . Then on the next clock pulse t_1 , the true output, and therefore output P_1 , will go to a logic 1 level. The complement output of stage RC_1 will go to a logic 0 level so that the output of AND gate 16 will go to a logic 0 level. The logic 1 level of the true output of stage RC_1 is applied back to the K input of stage RC_1 and to the J input of stage RC_2 .

On clock pulse t_2 , stage RC_1 will complement back to a logic 0 state as a result of the logic 1 level at the K input, and stage RC_2 will complement to a logic 1 state as a result of the logic 1 level at the J input so that output P_2 goes to a logic 1 level. The complement output of stage RC_2 will go to a logic 0 level so that the output of gate 16 will remain at a logic 0 level. The logic 1 level of the true output of stage RC_2 is then applied to the K input of stage RC_2 and to the J input of stage RC_3 . On clock pulse t_3 , stage RC_2 complements back to a logic 0 state, and stage RC_3 complements to a logic 1 state, with output P_3 going to a logic 1 level. The logic 0 level at the complement output of stage RC_3 maintains the output of AND gate 16 at a logic 0 level. The logic 1 level of the true output of stage RC_3 is fed back to the K input of stage RC_3 and to the J input of stage RC_4 . On clock pulse t_4 , stage RC_3 complements back to a logic 0 state, and stage RC_4 complements to a logic 1 state, thus raising output P_4 to the logic 1 level. The complement output C of stage RC_4 goes to a logic 0 level to maintain the output of gate 16 at a logic 0 level. On clock pulse t_5 , stage RC_4 goes to a logic 0 level. All four outputs P_1 – P_4 are then at a logic 0 level. The complement outputs C of all four stages

$RC_1 - RC_4$ are at a logic 1 level, the output of AND gate 16 is therefore at a logic 1 level. Then on clock pulse t_6 , stage RC_1 complements to a logic 1 state and the cycle is repeated.

The inverting amplifier 18 produces a clock pulse for the Johnson counter 19 only in response to each negative going transition of the true output T of stage RC_4 of the ring counter 12. When first set in operation, the Johnson counter can assume an illegal mode of operation. However, in the illegal mode, stages JC_1 and JC_4 do assume a logic 0 state at the same time. At this time, stages JC_2 and JC_3 are immediately reset to the logic 0 state before the next clock pulse, at which time all four stages will be in the logic 0 state. Then on the next four successive clock pulses, stages JC_1 , JC_2 , JC_3 and JC_4 complement to the logic 1 state, and then on the following four clock pulses, stages JC_1 , JC_2 , JC_3 and JC_4 successively complement back to the logic 0 state. The cycle is then repeated. As a result of the connections of the true and complement outputs of the binary stages $JC_1 - JC_4$ to the inputs of gates $G_1 - G_8$, outputs $T_1 - T_8$ go to a logic 1 level when the true outputs of the stages $JC_1 - JC_4$ are at the logic levels indicated in the truth table of FIG. 3. Thus, the outputs $T_1 - T_8$ successively go to a logic 1 in the sequence illustrated in the timing diagram of FIG. 4, the clock pulses from inverter 18 being represented by dotted lines $X_1 - X_{10}$.

The coincidence between the operation of the ring counter 12 and the Johnson counter 19 is illustrated in the timing diagram of FIG. 5. The logic levels of the four outputs $P_1 - P_4$ of the ring counter 12 are indicated by the time lines 31-34. Similarly, the logic levels of the eight outputs $T_1 - T_8$ are represented by the time lines 35-38. Assume that prior to time t_0 the stages $RC_1 - RC_3$ are in the logic 0 state and stage RC_4 is in the logic 1 state so that output P_4 of the ring counter 12 will be at a logic 1 level as represented by pulse 34a. Assume also that stages $JC_1 - JC_3$ are in the logic 0 state and that stage JC_4 is in the logic 1 state so that only output T_8 is at a logic 1 level. Then on clock pulse t_0 , P_4 will go to a logic 0 and all outputs $P_1 - P_4$ of the ring counter will be at a logic 0 level. As the output P_4 goes to a logic 0 level, inverter 18 emits clock pulse X_1 which complements stage JC_4 to a logic 0 state so that output T_1 will go to a logic 1 level as illustrated at 35a. However, some propagation delay results before the negative going transition of the true output of stage RC_4 of the ring counter appears as a positive going transition at output T_1 of the Johnson counter. This is represented for simplicity as a delay occurring in inverter 18, which indeed does produce some delay, but also occurs in the Johnson counter. The total delay may be approximately one-half the period of oscillator 14. Thus, output T_1 goes positive after the occurrence of clock pulse t_0 , but before the occurrence of clock pulse t_1 . Then upon the occurrence of clock pulses t_1 , t_2 , t_3 and t_4 , the outputs $P_1 - P_4$ successively go to the logic 1 level as indicated by pulses 31a, 32a, 33a and 34a, respectively. Then after the fifth clock pulse, the negative going portion of pulse 34a produces a clock pulse X_2 at the output of inverter 18. Clock pulse X_2 increments the Johnson counter 19 so that output T_1 goes to a logic 0 level at 35b and output T_2 goes to a logic 1 level at 36a prior to the occurrence of clock pulse t_6 , and during this interval all of the outputs $P_1 - P_4$ are at a logic 0 level. Then outputs $P_1 - P_4$ again successively rise to a logic 1 level on clock pulses $t_6 - t_9$ as represented by the pulses 31b, 32b, 33b and 34b. Then as the output P_4 goes to a logic 0 level at the end of pulse 34c, another clock pulse X_3 is generated by inverter 18 which increments the Johnson counter 19, causing output T_3 to go to a logic 0 level as represented at 37a. This cycle is repeated for each of the eight outputs $T_1 - T_8$.

Any one of the outputs $P_1 - P_4$ can be ANDed with any one of the outputs $T_1 - T_8$, as represented by AND gate 40 in FIG. 1. The AND gate 40 will then produce a logic 1 output only

during period 01 between clock pulse t_1 and clock pulse t_2 . Thus, four distinct pulse periods occur during each of the eight counts of the Johnson counter 19, giving a total of 32 sequential counts which can be individually identified. For example, periods 01-04 (see the bottom of FIG. 5) are defined by a logic 1 level at output T_1 and outputs $P_1 - P_4$, respectively. Periods 05-08 are defined during the period when output T_2 is at a logic 1 level, periods 09-012 during the period outputs T_3 is at a logic 1 level, etc. By changing the logic level of outputs $T_1 - T_8$ during the delay period when the four outputs $P_1 - P_4$ of the ring counter are at a logic 0 level, the possibility of any spurious spikes being produced from the gate 40, or the other similar gates represented by gate 40 which may be used to identify one of the 32 periods, is eliminated.

Although a preferred embodiment of the invention has been described in detail, it is to be understood that various changes, substitutions and alterations can be made therein without departing from the spirit and scope of the invention as defined by the appended claims.

I claim:

1. The clocking system comprising a first counter having a plurality of outputs for sequentially producing a pulse on each output and after a delay count when the outputs from said first counter are zero repeating the sequence, said first counter comprising a plurality of synchronous binary stages, means serially interconnecting the stages such that after the first stage complements to a logic 1 state, the succeeding stages sequentially complement, on successive clock pulses, from a logic 0 state to a logic 1 state, means connecting an output of each stage to an input of each stage for causing each stage to complement back to the logic 0 state on the first clock pulse after going to the logic 1 state, delay means connecting an output of the last stage to an input of the first for complementing the first state to the logic 1 state on the first clock pulse after the last stage goes to the logic 0 state, a second counter having a plurality of inputs and outputs for sequentially producing a pulse on each output and then repeating the sequence, delay means connecting an output of the last stage of said first counter to the clock inputs of said second counter such that the second counter is incremented after the last stage of the first counter goes to a logic 0 state and before the first stage of the first counter goes to a logic 1 state during the delay count of the first counter when the outputs from said first counter are 0 whereby any one of the outputs of the first counter may be ANDed with any output of the second counter so that any one of a total number of sequential periods equal to the product of the number of outputs of the first counter and the number of outputs of the second counter can be specifically identified without spurious spikes being produced in said total number of sequential periods.

2. The clocking system defined in claim 1 wherein the second counter is comprised of a plurality of synchronous binary stages, means serially interconnecting the binary stages such that after the first complements to the logic 1 state, the remaining stages sequentially complement to the logic 1 state on successive clock pulses, and means interconnecting the outputs of the last stage to the inputs of the first stage for causing the first stage to complement to the logic 0 state on the next clock pulse after the last stage goes to the logic 1 state and to complement to the logic 1 state on the next clock pulse after the last stage goes to the logic 0 state, and logic gate means connected to the outputs of the binary stages of the second counter including a number of outputs equal to twice the number of binary stages of the second counter for sequentially producing a logic 1 level on each output on successive clock pulses to the second counter and repeating the sequence.
